The ornamental design for a lamp, as shown and described.

DESCRIPTION

FIG. 1 is a perspective view from above one end and one side, of a first embodiment of a lamp showing my new design;

FIG. 2 is a side elevational view of the first embodiment of the lamp the opposite side being a mirror image;

FIG. 3 is an underplan view of the base of the first embodiment of the lamp;

FIG. 4 is an elevational view of the other end of the first embodiment of the lamp;

FIG. 5 is a perspective view from above one end and one side, of a second embodiment of a lamp showing my new design;

FIG. 6 is a side elevational view of the second embodiment of the lamp the opposite side being a mirror image;

FIG. 7 is an underplan view of the base of the second embodiment of the lamp; and,

FIG. 8 is an elevational view of the other end of the second embodiment of the lamp.

Wall mounting apertures, studs and fasteners on the base are shown in broken lines for illustration purpose only.
